(57) **CLAIM**

The ornamental design for a utility vehicle rear body, as shown and described.

DESCRIPTION

FIG. 1 is an isometric view of a utility vehicle rear body, such as a golf car and a small maintenance, shuttle or cargo vehicle rear body;

FIG. 2 is a top view thereof;

FIG. 3 is a front view thereof;

FIG. 4 is a rear view thereof;

FIG. 5 is a left side view thereof;

FIG. 6 is a right side view thereof; and,

FIG. 7 is a bottom view thereof.

The broken lines in the drawings illustrate portions of the utility vehicle rear body that form no part of the claimed design.
